DESIGN FOR A PHONOGRAPH

David C. Rockola, Chicago, Ill., assignor to Rock-Ola Manufacturing Corporation, Chicago, Ill., a corporation of Delaware

Application December 9, 1937, Serial No. 73,492

Term of patent 14 years

To all whom it may concern:

Be it known that I, David C. Rockola, a citizen of the Dominion of Canada and a resident of Chicago, in the county of Cook and State of Illinois, have invented a new, original, and ornamental Design for a Phonograph, of which the following is a specification, reference being had to the accompanying drawings, forming a part thereof,

In the drawings:

Fig. 1 is a side perspective view;
Fig. 2 is a top view; and
Fig. 3 is a side elevation of a phonograph embodying the novel design.

I claim:

The ornamental design for a phonograph, as shown,

DAVID C. ROCKOLA.
